CLAIM

We claim, the ornamental design for the vehicle mountable football cooler, as shown and described.

DESCRIPTION

FIG. 1 is a rear view of a vehicle mountable football cooler, showing our new design;

FIG. 2 is a front view thereof;

FIG. 3 is a left view thereof;

FIG. 4 is a right side view thereof;

FIG. 5 is a top side view thereof; and,

FIG. 6 is a bottom view thereof.

The broken lines are for illustrative purposes only and form no part of the claimed design.
